ADJUSTABLE SWEAT BAND FOR HATS

William C. Gray, St. Charles, Ill., assignor to
Jesse B. Hawley, Geneva, Ill.

Application June 25, 1935, Serial No. 28,321

8 Claims. (Cl. 2—183)

The present invention relates to means for supporting and holding a hat on the head of the wearer and has particular reference to hats of the type which is of a given size and larger than the wearer's head and is suspended by the head or sweat band which itself is fitted to the particular size of the head of the wearer.

Among the objects of the invention is to provide a novel head or sweat band device which 10 is adjustably connected to the hat in such a way that as the hat is put onto the head the band readily fits the head.

Another object of the invention is to provide a novel head or sweat band device which is 15 readily attachable to and detachable from the hat when it is desired to replace the band or to substitute a new band or the like.

Another object of the invention is to provide a novel means for connecting the head or sweat 20 band to the hat.

Other objects, advantages, capabilities, features, and the like, are comprehended by the invention as will later appear and as are inherently possessed by the invention.

25 Referring to the drawing:

Fig. 1 is a bottom plan view of a hat and head or sweat band device constructed in accordance with the invention;

Fig. 2 is a fragmentary sectional view taken 30 through a part of the hat to show the connection between the hat and the band.

Fig. 3 is a fragmentary view in elevation showing the adjustability of the band;

Fig. 4 is a perspective view of an element 35 of the connection between the hat and band;

Fig. 5 is a fragmentary sectional view taken through a part of the hat and band and showing an alternate form of connecting means; and,

Fig. 6 is a fragmentary view in elevation of 40 the form shown in Fig. 5 showing the adjustability of the band.

Referring more in detail to the drawing the embodiments selected to illustrate the invention are shown in connection with a hat 1 having a 45 crown 2 and a brim 3. The crown may have design features such as a boss 4 to represent a top knot, ridges 5 to represent seams or the like and ribs 6 to represent folds or pleats or the like.

50 The hat is preferably composed of accreted fibrous material molded upon a porous former or die by the accretion of treated fibres upon the contoured surface of the molding die, and suitably pressed, dried and coated, as more fully disclosed in the co-pending applications of Jesse B. Hawley and Edward C. Sloan et al., Serial Nos. 4866 and 4862 respectively and both filed on Feb. 4, 1935.

At the juncture 7 between the crown 2 and 55 the brim 3 are located connecting means 8

which, in the particular embodiment selected to illustrate the invention, is in the form of resilient strips which may be of metal or the like. Each strip is bent at a bend 9 which is disposed at an angle to the length of the strip so as to 5 provide the limbs 10 and 11 extending in different directions as shown more particularly in Figs. 3 and 6. The free end of the limb 10 has an aperture 10^a for receiving the shank of an eyelet or rivet 12 passing through a suitable aperture provided in the juncture 7 of the hat (Figs. 2 and 5), the rivet 12 having an inner flange 13 overlying the apertured end of the limb 10, and an outer flange 14 overlying the apertured portion of the hat juncture 7. The limb 10 may have 15 projections 15 for preventing rotation of the connecting member 8 about the rivet 12. The limb 11 is designed for sliding or adjusting connection with the sweat band 17, and may have a slot 16 for clearing the rivet of the connecting 20 means secured to the sweat band.

In the form shown in Figs. 2 and 3, the limb 11 is shown as slidably disposed in a clip 18 and between the bends 19 and 20 of the normally bent-over fingers 21 and 22. This clip 18 has a 25 base or back 23 suitably apertured to receive the shank of an eyelet or rivet 24 having an inner flange 25 and an outer flange 26 between which the apertured portion 27 of the sweat band 17 and the clip base 23 are clamped. The slotted part 30 of the limb 11 of the connecting member 8 is so arranged as to clear the flange 26 of the rivet 24, or, in other words, the flange 26 extends in the slot 16.

To assemble or detach the sweat band, the 35 fingers 21 and 22 of the clip 18 are either in or bent to the extended positions shown in dotted lines in Figs. 2 and 3 whereby the slotted limb 11 may be located in place with or removed from the clip, the slot 16 providing for clearing the 40 rivet, such as the flange 26 thereof. After the limb is in place, the fingers 21 and 22 are bent into the full line positions shown thereof in Figs. 2 and 3.

In the form shown in Figs. 5 and 6, the slotted 45 limb 11 slides on the eyelet or rivet 28 and in between washers 29 and 30 carried by the shank of the rivet 28, the latter having an inner flange 31 for engaging the apertured portion 27 of the sweat band 17 and an outer flange 32 overlying 50 the washer 29.

The sweat band is in the form of a strip of 55 material which has sufficient stiffness to be held in some general form and still is resilient enough to give for changing the size of the band. In the drawing, this head or sweat band is shown to be of oval shape and is connected at spaced points to the connecting or supporting strips 8 as clearly indicated in the drawing. The band has free end portions 33 and 34 which may be 60

adjustably connected together by any suitable means. In the particular embodiment selected to illustrate the invention the end portions 33 and 34 are provided with eyelets 35 and 36 through which may be threaded a cord 37 which may be elastic or non-elastic as desired, in such a manner that the ends 35 and 36 of the cord may be tied together to form a knot 40. By tying the cord with greater or less length of the laps of the cord 37, it will be apparent that the end portions 33 and 34 of the sweat band may be at a greater or less distance with respect to each other accordingly increasing or decreasing the size of the sweat band.

15 In making adjustments of the size of the sweat band each element 8 is capable of sliding with respect to the rivet 24 or 28 as the case may be. In the former case the slotted limb 11 slides in the clip 18 and in the latter case the slotted limb 20 slides between the washers 28 and 30. This sliding action takes place automatically as the sweat band is extended in peripheral lengths or is decreased in length. In this way the resilient members 8 compensate for adjustment or variation 25 in size of the hat band. There is sufficient friction between the relatively slidable parts as to normally hold the elements in adjusted position.

The members or elements 8 are also flexible 30 so that as the sweat band is forced upon the head, when placing the hat upon the head, and is expanded at the lower portion of the sweat band, the members 8 will be flexed in compensation of that movement of the sweat band. In other words, the hat is supported by way of the elements 8 in a sort of suspension from the sweat band, the sweat band being supported on the head 35 of the wearer. It will also be noted that the sweat band is spaced from the lower portion of the crown of the hat so that there is provided an air space between the sweat band and the hat 40 so as to afford free circulation of air. By reason of the resiliency or flexibility of the members or elements 8 when the sweat band is upon the head 45 there is a certain amount of tension or pressure tending to hold the sweat band snug yet comfortably upon the head of the wearer.

A chin strap 41 may also be secured to the hat by any suitable securing connecting elements, 50 such as glove snaps 42 and 43 as shown in Fig. 1 of the drawing.

It will be apparent from the above description that the sweat band shown in Figs. 2 and 3 is easily detached from or attached upon the hat, 55 by merely opening up the fingers of the clips and inserting the slotted limb of each connecting member 8 in place and then bending back the fingers of the clip. One advantage of having the sweat band (and also the chin strap) detachably connected to the hat is that the hats may all be made of one size and when the hat is to be used by the wearer of a given size of head, the sweat band which is nearest to the size of his head may be easily connected in place in the clips as explained above. If the sweat band 60 is not of the exact size of the head adjustment may be made by tying the knot 40 at the proper place. The chin strap which has been chosen for the person to wear the hat may also be easily snapped into place.

70 Another advantage is that should the hat be used by a person for a short period of time, such

as by an Army man, and when the wearer has ceased to use it, the hat may then be issued to another Army man but a new sweat band and a new chin strap will be attached into place in lieu of the ones formerly used by the previous 5 Army man. This will obviate the necessity of issuing an entirely new hat to the second man.

Another advantage is that when it is desired to clean the hat, it is an easy matter to remove the sweat band and the chin strap and after the 10 hat has been cleaned it is as easy to replace them.

While I have herein disclosed a few illustrative embodiments of the invention, it is to be understood that the invention is not limited there-to but may comprehend other constructions, details, arrangements of parts, features, and the like without departing from the spirit of the invention.

Having thus disclosed the invention, I claim: 20

1. In a hat having a sweat band, connecting means for connecting the band to the hat and comprising resilient limbs respectively connected to said band and hat, and means for slidably connecting one of said limbs to the band. 25

2. In a hat having a sweat band, a member for connecting the hat and band, means for securing said member to the hat, a clip secured to the band, said member having a portion slidably connected to said clip. 30

3. In a hat having a sweat band, a member for connecting the hat and band, means for securing said member to the hat, and a clip secured to the band, said member having a portion slidably connected to said clip, said clip comprising 35 bendable fingers for the attachment and detachment of said member.

4. In a hat having a sweat band, a resilient member for connecting the hat and band, means for securing said member to the hat, and a clip 40 secured to the band, said member having a portion slidably connected to said clip.

5. In a hat having a sweat band, a resilient member for connecting the hat and band, means for securing said member to the hat, and means 45 for slidably connecting said member and said band.

6. In a hat having a sweat band, means for connecting the band to the hat and comprising a bent member, one end of said member being 50 pivotally connected to the hat and the other end being slidably connected to the band whereby to provide for adjusting the band to various sizes.

7. In a hat having a sweat band, means for connecting the band to the hat and comprising 55 a bent member provided with limbs, means for connecting the free ends of said limbs respectively to the hat and to the band, one of said free ends being provided with a slot whereby to provide for sliding movement between the band 60 and the means, the other of said free ends being pivotally connected to the hat.

8. In a hat having a sweat band, means for connecting the band to the hat and comprising a bent member, one end of said member being 65 pivotally connected to the hat and the other end being slidably connected to the band whereby to provide for adjusting the band to various sizes, and means for holding said band in adjusted position.

WILLIAM C. GRAY. 70
